COMBINED SHUT-OFF AND DRAINAGE
VALVING MEANS

Jerome De Haes, Chicago, Ill., assignor of one-half to A. Trevor Jones, Oak Park, Ill.

Application May 31, 1934, Serial No. 728,365

14 Claims. (Cl. 277—30)

This invention relates to combined shut-off and check valving means, more particularly for steam radiators or the like.

In steam heating systems which are not provided with return pipes for the condensation products of the system, leakage of water from the radiators when the steam is wholly or partially shut off has always been a serious menace to property. When the valve at the radiator is shut off, in the absence of a return pipe, the water condensed in the radiator has no means of escape and gradual accumulations of such water will cause disagreeable knocking when the steam is again turned on, frequently accompanied with a discharge of the water upon the floor. Also if the radiator is not shut off tightly, the water may not be able to escape past the valve, but some steam may still be admitted, which will condense in the radiator and rapidly swell the accumulations of water therein so that serious leakage of the radiator follows inevitably.

An important object of the present invention is to provide valving means, desirably in a unitary structure, of simple and economical construction, including a main valve and a check valve carried by the main valve. When adapted for use with steam radiators to correct the difficulties above referred to, for which the invention has particular utility, admission of steam to the radiator may be prevented, while at the same time the water condensing therein may be permitted to drain off through the same pipe through which steam is carried, thus avoiding the necessity for the expensive installation of a return pipe system.

Other uses and advantages of the invention will be apparent from the following description, taken together with the accompanying drawings in which—

Figure 1 is a vertical sectional view of a main valve member embodying one form of my invention;

Figure 2 is a section taken on the lines 2—2 of Figure 1, looking downward;

Figure 3 is a section taken on the line 3—3 of Figure 1, looking upward;

Figure 4 is a perspective view showing parts of the structure of Figure 1 in separated relation;

Figure 5 is a vertical sectional view similar to Figure 1, of a main valve member with my invention, in a different aspect, applied thereto, a fragmentary portion of a valve stem being shown connected to the main valve part;

Figure 6 is a top plan view of the main valve part of Figure 5, with the valve stem removed;

Figure 7 is a bottom plan view of the structure of Figure 5; and

Figure 8 is a vertical sectional view on a somewhat smaller scale, partly in elevation, of an exemplary complete valving means including my invention.

Referring first to Figure 8 of the drawings, it will be noted that I have shown a conventional valve body 10 having integral screw-threaded male and female nipples respectively 11 and 12 for attachment, by the nipple 11 to the usual steam radiator or the like (not shown) used for heating purposes. By the nipple 12, the usual steam pipe is attached and a passage 13 through the valve body communicates thus with both the radiator and the supply pipe. A bonnet 14 caps the valve body 10 and carries the usual valve stem 15, having a hand wheel or the like at the top for annular rotation, this wheel being not here shown. As is well known, rotation of the stem 15, by reason of threads 16 on the valve stem engaging with similar threads in the bonnet 14, causes the main valve B to be moved toward or away from the valve seat 17 to close or open the passageway 13 and thus exclude or permit the entry of steam from the supply pipe to the radiator, in a well-known manner.

The main valve part of the valving means shown in Figure 8 may be constructed, in accordance with my invention, in forms, for example, here shown as A and B.

Referring first to the A structure, as shown in Figure 1, this includes a generally cylindrical member 18 desirably formed of metal, and having an annular valve face 19 in this instance provided by a gasket ring 20 set into an annular recess in the flange-like face 21 of the member 18 and desirably formed of a composition material suitable for providing a tight seal with an annular valve seat such as the valve seat 17, shown in Figure 8.

Desirably carried by the member 18 centrally of the main valve face 19, is auxiliary valving means constructed in accordance with my invention and in the nature of a check valve mechanism brought into operation when the main valve is in closed position with respect to the passage through the valve body, that is in this instance when the main valve face 19 is in tight engagement with a valve seat such as 17.

In the illustrative construction shown in Figures 1 to 4 inclusive, I provide an auxiliary passageway through the main valve structure A including ducts 23, of which there are in this instance three, leading through the member 18 and

50

55

to an aperture 24 here shown centrally located in a transverse wall 25 in the member 18. The passageway through the member A also includes, as shown in Figure 1, a hollow metal cylinder 26 suitably secured to the member 18 about the wall 25 as by a snug telescoping engagement, the member 18 being grooved for this purpose as at 27 circumferentially of the wall 25 and within the area of and concentric with the valve face 19.

10 The cylinder, for the purposes of my invention, is below the valve seat 17 when the main valve is closed.

At its lower end, the cylinder 26 is partially closed by another transverse wall 28 having a central aperture 29 therein. The aperture 24 in the upper transverse wall 25 and the aperture 29 in the lower transverse wall 28 are adapted to be closed by a plate or disk 30 for the upper aperture and 40 for the lower aperture. The plate 30 is loosely held in a position closely adjacent to the aperture 24 by a foraminated support 31 here shown as a metallic disk suitably secured in the cylinder 26 spaced a relatively short distance below the transverse wall 25 and having perforations 32, in this instance three of these, therein and distributed circumferentially about the disk so as to define a larger area than that of the disk 30 so that the perforations 32 cannot at any time be all covered by the disk 30. The aperture 29 in the lower transverse wall 28, also in the form of a disk suitably secured in the lower end of the cylinder 26, is similarly adapted to be closed by the disk 40, loosely held in position adjacent the wall 28 by another foraminated support 34 somewhat similar to the support 31 and also having a plurality of perforations 35 therein. The support 34, however, may be secured to the cylinder 26 as a partial closure for the lower end thereof by means of the annular flange 36 snugly telescoping over the lower end of the cylinder. In order to further assure that the disks 30 and 40 respectively will not close the perforations 32 and 35 respectively, inwardly directed projections or nubs 37, 38 respectively are provided on the supports 31 and 34 to space the disks away from their supports and to project them toward the transverse walls.

The disks 30, 40 and other associated parts just described, constitute somewhat in the nature of a pair of check valves spaced apart vertically on the main valve A and adapted normally to close the auxiliary passage through the valve A defined by the ducts 23 and the hollow cylinder 26, when there is steam pressure in the steam pipe leading to the valve body 10 and when the valve A is in closed position, as when the valve face 19 is in tight engagement with a valve seat such as the valve seat 17. It will be understood that the disks 30, 40 being of substantially smaller diameter than the tube 26, and being loosely held between their respective transverse walls and foraminated supports, are moved by the steam pressure beneath them, if any, each into engagement with their respective transverse walls so as to close the apertures through these walls.

When the lower aperture 29 is closed, as just described, the space 31 between the pair of check valves in the cylinder 26 affords a float chamber for a float 41 loosely received therein, which, in accordance with my invention, is adapted to control a by-pass passage through the valve A communicating with the ducts 23 independently of the apertures 24 and 29.

In the construction now described, such a by-pass is provided by a pair of relatively small

diameter tubes 42 and 43. The tube 42 may be mounted on the disk forming the transverse wall 28 to pass upwardly therethrough substantially tangent to the periphery thereof and to lie alongside of and in abutment with the longitudinally extending wall of the cylinder 26. The tube 43 may be somewhat similarly carried by the disk forming the foraminated support 31 at the upper part of the cylinder 26, the tube 43 passing through this disk and also passing through a bore 10 44 in the transverse wall 25. As best shown in Figure 2, the counter-bore 45 in the member 18 surrounding the aperture 24 and communicating with the ducts 23, is laterally enlarged as at 46 to communicate also with the tube 43. 15

The tubes 42, 43 both extend and open into the float chamber 39, the tube 42 upwardly, and the tube 43 downwardly, and these tubes are aligned vertically with their adjacent ends spaced apart within the float chamber 39, the tube 42 being 20 desirably the longer of the two so as to extend up toward the upper portion of this float chamber. Between the adjacent ends of the tubes 42, 43 is carried by the float 41 a pair of needle valves 47, 48, in this instance formed integrally 25 at opposite ends of a small solid metallic cylinder 49 rigidly carried by a rigid laterally extending arm 50 suitably securely attached to the float 41. The needle valves 47, 49 are shown in the form of conical faces at the lower and upper ends 30 respectively of cylinder 49 and are adapted to seat in the mouths 51, 52 (Fig. 4) respectively of the tubes 42, 43 to close one or the other of these tubes, as the case may be. In order to guide the needle valves in their movement, I have desirably shown the cylinder 49 extended at each end centrally of the conical faces forming the needle valves 47, 48 to form rod-like reduced extensions 53 which project into the tubes.

Surrounding the upper rod-like extension 53 40 I have shown a compression coil spring 54 which seats at its upper end against an inwardly directed annular flange 55 of the tube 43 and at its lower end against the needle valve 48. Thus the action of the spring 54 supplements the action of gravity in maintaining the float 41 resiliently in its lowermost position in the float chamber 39 with the needle valve 47 closing the tube 42.

The operation of the structure just described 50 is as follows: When the main valve A is in closed position as already referred to, it is desired to prevent steam from passing into the radiator, while at the same time permitting water to drain therefrom through the same pipe which carries the steam. In the first place, if there is steam in the pipe below the main valve, the pressure of this steam will cause the disk 40 to close the aperture 29. At the same time, if there is no water in the float chamber 39, as 60 there would not be immediately when the disk 40 is moved to closed position, the float 41 will be at its lowermost position under the influence of gravity and the spring 54, to close the tube 42. Unless the steam pressure is sufficient to 65 overcome the force both of gravity and of the spring 54, no passage through the valve A will be found by the steam. The strength of the spring 54 may be predetermined for a predetermined steam pressure desired to be worked with. For example, spring 54 may be of a strength sufficient to resist the action of steam pressure less than say 5 lbs., assuming that this would be the maximum steam pressure normally car- 75.

ried by the system in the vicinity of the radiators.

With the passage for the steam thus closed, the water of condensation accumulating in the 5 radiator may pass through one or more of the ducts 23, then through either or both of the aperture 24 and the tube 43, and into the float chamber 39. The aperture 24 will be assumed to be open at this time, since by reason of the 10 orifice through the wall 25 provided by the tube 43, pressure is equalized on both sides of the disk 30, that is, above and below the disk 30, so that water is driven into the chamber 39. As the water accumulates in the float chamber 15 39, the float, under the influence of the water, supplemented by the steam pressure below it, will be raised against the action of the spring 54 to open the tube 42. This will permit steam to pass through the tube 42 and into the float 20 chamber 39, equalizing the pressure on opposite sides of the disk 40 and permitting the water in the float chamber to open the aperture 29, the water draining down into the steam pipe. At the same time, the float upon rising to its upper 25 most position will close the tube 43 by the needle valve 48, and the pressure of steam in the float chamber will move the disk 30 to close the aperture 24, thus preventing entry of the steam to the radiator. As soon as the water has drained 30 from the float chamber 39, however, the action of the spring 54 supplementing the action of gravity on the float 41, will overcome the steam pressure and will again move the needle valve 47 to close the tube 42, whereupon the pressure 35 will be again on the bottom side of the disk 40 and will move this disk to again close the aperture 29 and to maintain this closed until water again accumulates in the float chamber 39, to repeat the cycle. It will be understood that 40 the disks 30 and 40 are of sufficient area to always close the apertures 24 or 29 as the case may be when the disks are moved into abutment with their respective transverse walls as described.

45 While the auxiliary valving means as a whole is below the valve seat 17, so that water may drain thereinto, the upper ends of the ducts 23 or 67 (Fig. 5) are advantageously above the lower level of the radiator interior, so that sediment cannot run into the ducts to obstruct them, while at the same time any water standing in the radiator up to the level of the upper ends of the ducts 23 can drain out therethrough.

The wafer-like discs 30, 40 and 65 (Fig. 5) 50 function somewhat on the principle of a telephone transmitter diaphragm, in that they vibrate with a breath of air or steam, and will therefore prevent passage or leaking of the steam thereby even though there is no substantial pressure of steam in the system. For this reason, my device will function rapidly and positively to close or open the drainage passage by reason of the vibrating, loosely-held, wafer-like valve which I have shown.

65 In steam-heating systems for apartments and office buildings, for example, where the steam is turned off entirely at night, a sub-combination of my invention may be used advantageously, omitting the float and float chamber shown in 70 Figures 1 to 4, and thus also omitting one of the check valves. This latter construction is illustrated by my simplified B valve structure shown in detail in Figures 5 to 7 inclusive.

This B structure comprises a main valve part 75 56 generally similar to the part 18 of the A

structure and having the annular gasket 57 providing a valve face. Instead of the cylinder 26, however, the B structure may be extended downwardly to form the integral part 58 having the transverse wall 59 therein with a central aperture 60. The part 58 at 61 is exteriorly threaded below the transverse wall 60 to have screwed thereon the interiorly threaded flange 62 of the member 63, which, by reason of the perforations 64 therein serves both as a partial closure for 10 the portion 58 and also as a foraminated support for the disk 65 loosely held between the member 63 and the transverse wall 60. The inwardly-directed axially aligned projection or nub 66 spaces this disk from the perforations 64 15 and toward the transverse wall 59. The perforations or foraminations in the partial closure are desirably offset axially so as to be off centre of the closure.

In the operation of this B structure, when the 20 main valve is moved to closed position, as indicated in Figure 8, the steam is shut off from the radiator by reason of the fact that the main valve closes the passage 13, and also if there is steam pressure still in the pipe below the valve 25 mechanism, this pressure will force the disk 65 toward the transverse wall 59 and close the aperture 60, thus closing the auxiliary passage through the main valve B. When the steam is turned off entirely, as at night, any water condensing in 30 the radiator will drain down through the ducts 67 and into the hollow interior 68 of the main valve, and down through the aperture 60 and perforations 64, back into the steam pipe, the absence of fluid pressure on the under side of the 35 disk 65 permitting this to drop by gravity to a position somewhat as shown in Figure 5, and permitting the escape of the water.

An important aspect and advantage of my invention is that the valve structures A and B can 40 be made separately as independent units and can be attached to an existing conventional valve structure as shown in Figure 8. For this purpose the shanks of the members 18 and 56 respectively of the structures A and B are interiorly 45 threaded as at 69 and 70 respectively to receive a threaded coupling nut such as the nut 71 (Figs. 5 and 8) which is threaded as at 72 to be screwed into the shank of the main valve and thus to cause the main valve to become an operative part 50 of the rotatable valve stem 15. There is desirably a rotative movement permitted between the valve stem 15 and the nut 71, by reason of a somewhat loose connection therebetween, so that when the main valve is screwed down by the stem 55 15 to tight engagement with the valve seat, the valve stem may turn to force the valve downwardly, without also rotating it, since the rotation of the main valve during its engagement with the valve seat would cause unnecessary 60 wear between these parts. A head 73 at the lower end of the valve stem permits this lost motion connection while preventing disengagement of the valve stem and main valve.

Obviously, the invention is not limited to the 65 details of construction shown herein for purposes of exemplification.

Having described my invention, I claim:

1. In valving means of the character described, the combination with a valve body having a passage therethrough and a valve seat in said passage, of a main valve vertically movable toward and away from said seat to close and open the passage; an auxiliary passage through said main valve; an upper transverse wall in said auxiliary 75

passage having a central aperture therethrough; a foraminated upper support closely adjacent to and beneath said upper transverse wall; an auxiliary valve member loosely carried by the support in position closely adjacent to said aperture; a lower transverse wall vertically spaced from said first-mentioned wall and support, said lower transverse wall also having an aperture therethrough; a lower foraminated support beneath the lower transverse wall; another movable member carried by said lower support adapted to close said second-mentioned aperture; a float between said lower wall and upper support; a pair of needle valves carried by the float; and orifices in said upper and lower transverse walls respectively closed by one of said needle valves when the float is in its uppermost or lowermost position respectively, said orifices providing a by-pass passage through said main valve independent of said auxiliary passage.

2. The structure of claim 1 wherein the float and the lower needle valve are maintained in lowermost position by the action of gravity and are movable upwardly from said lowermost position against the force of a spring.

3. The structure of claim 1 wherein said orifices are provided by vertically aligned relatively small diameter tubes passing through the said upper and lower transverse walls respectively and said tubes have their adjacent ends spaced apart between the upper support and the lower transverse wall, and the needle valves have rod-like reduced diameter extensions projected respectively into said tubes to guide the needle valves therein.

4. The structure of claim 1 wherein said orifices are provided by vertically aligned relatively small diameter tubes passing through the said upper and lower transverse walls respectively and said tubes having their adjacent ends spaced apart between the upper support and the lower transverse wall, and the needle valves are formed integrally and have reduced diameter rod-like extensions projecting into said tubes respectively to guide the needle valves in their up-and-down movement, and a compression coil spring is carried by the upper tube surrounding the rod-like extension received therein and having an upper bearing in said tube and a lower bearing on the upper needle valve.

5. In valving means of the character described, the combination with a valve body having a passage therethrough and a valve seat in said passage, of a main valve vertically movable toward and away from said seat to close and open the passage; an auxiliary passage through said main valve; an upper transverse wall in said auxiliary passage having a central aperture therethrough; a foraminated upper support closely adjacent to and beneath said upper transverse wall; an auxiliary valve member loosely carried by the support in position closely adjacent to said aperture; a lower transverse wall vertically spaced from said first-mentioned wall and support, said lower transverse wall also having an aperture therethrough; a lower foraminated support beneath the lower transverse wall; another movable member carried by said lower support adapted to close said second-mentioned aperture; a float between said lower wall and upper support; a needle valve carried by the float; and an orifice in the lower wall controlled by the needle valve.

6. A valve of the character described embodying a cylindrical metallic member screw-threaded at one end for engagement with a valve stem

and having an oppositely-directed annular valve face, said member having a passage therethrough surrounded by the annular valve face and said passage having a centrally apertured transverse wall therein, a partial closure for said passage, said partial closure having a plurality of foraminations therein offset axially of the closure, and a disk loosely enclosed between said closure and said wall, said disk being adapted to be moved in one direction by fluid pressure adapted to close said aperture and by fluid pressure in the opposite direction to open said aperture, the disk being supported in the latter position by the foraminated member.

7. The structure of claim 6 wherein there are a plurality of inclined drain ducts passing through the member into communication with said passage, said ducts having their upper openings closely adjacent but above said valve face.

8. The structure of claim 6 wherein the said closure carries an inwardly directed projection axially aligned engaging the disk, spacing it from the foraminated portion of the closure and maintaining it nearer the said wall.

9. The structure of claim 6 wherein the said closure and member are provided with screw-threaded engagement.

10. In valving means of the character described, the combination with a valve body having a passage therethrough and valve seat in said passage; of a main valve movable toward and away from said seat to close and open the passage; a hollow cylinder carried by the main valve in said passage at least partially below said valve seat when the main valve is closed, a duct in the said main valve communicating with the cylinder and having an opening exteriorly of the main valve in the immediate vicinity of said valve seat; a transverse wall in said cylinder having an aperture therein providing a passage therethrough said aperture being below said valve seat when the valve is closed; a plate movable into and out of abutment with said wall to close said aperture; and a foraminated support for said plate loosely maintaining the plate below said wall in position closely adjacent to said wall.

11. In valving means of the character described, the combination with a valve body having a passage therethrough and a valve seat in said passage, of a main valve movable toward and away from said seat to open and close the passage; an auxiliary passage through said main valve extending below said valve seat in all normal positions of the valve body; and a check valve carried by the main valve below the valve seat for controlling the auxiliary passage, said check valve being in the form of a vibrating wafer-like plate loosely held by said main valve.

12. In valving means of the character described, the combination with a main valve having an annular valve face; of a passageway through said main valve, a hollow receptacle carried by the main valve and projecting beyond the said annular valve face centrally thereof, said receptacle communicating with the passageway, an aperture in said receptacle a foraminated support carried by the main valve beyond the said aperture, and an auxiliary valve carried by the support for closing said aperture.

13. In valving means of the character described, the combination with a passageway, of a valve seat in said passageway, a main valve movable toward and from said valve seat to close or open the passageway, an auxiliary passageway

through the main valve, an auxiliary valve seat in said auxiliary passageway, a foraminated support carried by the main valve, and an auxiliary valve loosely carried between the foraminated support and the auxiliary valve seat, said auxiliary valve being free to move in one direction by the action of gravity to open the auxiliary passageway and in the other direction against the action of gravity to close the auxiliary passageway independently of the movement of the main valve.

14. In valving means of the character described, the combination with a common steam and drain passageway for a steam radiator or the like, of a fixed valve seat in said passageway, a main valve movable toward and away from

said fixed valve seat to close or open the passageway, an auxiliary passageway through the main valve, an auxiliary valve seat in said auxiliary passageway, means for accumulating liquid condensation in the common passageway, said auxiliary valve seat in the auxiliary passageway being below said means when the main valve is closed, and an auxiliary valve carried by the main valve movable by the weight of the liquid to open the auxiliary passageway, said auxiliary valve moving in directions to close and open the auxiliary passageway opposite to the movements of the main valve to open and close the common passageway.

JEROME DE HAES. 15
